HEAT TRANSFER SYSTEM

Marcus E. Fiene, Caldwell, N. J., assignor to General Electric Company, a corporation of New York

Application February 6, 1943, Serial No. 474,979

11 Claims. (Cl. 237—9)

The invention relates to heat transfer systems, particularly of the variable rate type adapted for automatic temperature regulating service and having a fluid vaporizing and condensing circulation wherein variation in the amount of circulating fluid controls the rate of heat transfer.

My Patent 2,289,879 discloses and claims a heat transfer system of the above type having a condensate accumulating reservoir and an electrically heated thermosiphon condensate pump variably energized from an outside power source under thermostatic control for controlling the amount of circulating fluid in the vaporizer and condenser heat transfer system by exchanging condensate between the reservoir and the system.

The principal object of the present invention is to provide an improved self-contained mechanical control system having a self-amplifying action in varying the amount of fluid circulating in a vaporizer and condenser heat transfer system to regulate the rate of heat transfer thereof.

A particular object is to provide an improved thermostatic double condensate circulation control system for a heat transfer system of the above type having a sensitive thermostat mechanically operating a selective condensate flow control vane to provide a substantially flat temperature regulation as well as a high amplification in the thermostatic control of the exchange of condensate between the system and an accumulating reservoir.

Another object is to provide an improved heat transfer system of the multiple circulation type in which a variable part of the condensate circulates directly between the condenser and the vaporizer while another variable part of the condensate circulates past a sensitive condensate flow directing vane that can selectively divert this part of the condensate into a condensate accumulating reservoir or permit the return circulation thereof to the vaporizer.

A further object is to provide an improved heat transfer system of the above type in which a pumping means operates continuously to circulate separately a continuous stream of condensate from the accumulating reservoir that can be diverted selectively by a sensitive control vane into the vaporizing and condensing heat transfer system or returned to the accumulating chamber.

A still further object is to operate the condensate pumping means continuously by thermosiphon action with heat obtained directly from the heat supply source of the heat transfer system.

A specific object is to reduce the noise of ebulli-

tion in such a thermosiphon type of pumping means in order to adapt the improved variable rate vaporizing and condensing heat transfer system for automatic room temperature control or other service where noise might be objectionable.

Further objects and advantages of the invention will appear in the following description of the accompanying drawing in which Fig. 1 is a schematic representation of a variable rate vaporizing and condensing heat transfer system embodying the present invention in a preferred form; and Fig. 2 is an enlarged sectional view of the improved double condensate flow control chamber employed in the system of Fig. 1 and showing the selective condensate flow diverting vane therein automatically operated by means of an external thermostat responsive to a temperature that is dependent upon the rate of heat transfer of the system.

As shown schematically in Fig. 1, the improved variable rate circulating fluid vaporizing and condensing heat transfer system is preferably of the hermetically sealed type from which the non-condensable gases are exhausted, and comprises the vaporizer 10 and the condenser 11 with which the condensate accumulating chamber 12 is connected through the dual condensate flow control chamber 13 having the selective condensate flow diverting or deflecting vane 14 pivotally mounted therein, as shown more clearly in Fig. 2. The vaporizer 10 preferably is heat insulated as shown. The condensate in the vaporizing chamber 10 is heated by means of the pipe 17 which may be continuously supplied with steam or other suitable heating medium and may be provided with the usual automatic air vent valve 18.

The condenser 11 is of the improved form having suitable heat dissipating fins 11a and a double downwardly sloping bottom 11b so that the vapor supplied from the vaporizer 10 through the conduit 20 will enter the condenser 11 centrally and after condensing therein will be drained as condensate therefrom by the two separate drain conduits 21 and 22. The part of the condensate drained from condenser 11 through conduit 21 will be returned directly to the vaporizer 10 through conduit 23. But the part of the condensate drained from condenser 11 through conduit 22 will pass into the top of the double condensate flow control chamber 13 adjacent one side of the control vane 14 in its vertical position, as shown in Fig. 1.

The dual condensate flow control chamber 13 communicates with the vaporizer 10 through the

drain conduits 24 and 23 to supply condensate thereto, and with the condensate accumulating chamber 12 through the drain passage 26 to supply condensate thereto. Preferably the drain conduit 24 extends slightly into chamber 13 to form a sediment trap 13a as shown. The accumulating chamber 12 also communicates with the control chamber 13 through the looped thermosiphon pump conduit 30 which extends from the bottom of accumulating chamber 12 to the top of the control chamber 13 with the condensate discharge end thereof located in closely adjacent parallel alignment with the discharge end of the condensate drain conduit 22 so as to discharge the two streams of condensate closely adjacent to the opposite sides of the flow control vane 14 in its vertical or neutral position as indicated in Fig. 1.

The looped thermosiphon pump conduit 30 is connected by means of the heat transfer block 31 to receive heat continuously from the steam pipe 17 into the leg thereof that communicates with the top of the control chamber 30. Hence, the looped thermosiphon pump conduit 30 functions continuously to circulate a stream of condensate from the accumulating chamber 12 into the top of the control chamber 13 adjacent the other side of control vane 14 in its vertical position as indicated in Fig. 1.

In order to reduce the noise of ebullition in the looped thermosiphon pump tube 30, a by-pass or cross connecting tube 32 interconnects the legs of the looped conduit 30 so as to provide a local circulation in the lower part of the loop 30a that receives heat from the heat transfer block 31. This local circulation prevents the superheating of the condensate above the value required to effect the thermosiphon pumping action and thereby avoids violent ebullition of the liquid adjacent the heat transfer block 31 which might cause undesirable noise. In order to equalize the pressures in the system, as well as to prevent the trapping in the accumulating chamber 12 of any non-condensable gases that may remain in the system after sealing, this chamber preferably is interconnected with the condenser 11 by the vent conduit 33.

As shown more clearly in Fig. 2, the double condensate flow diversion vane 14 is provided with pivotal mounting means comprising the shaft 40 and the pivot bearing posts 41 and 42, preferably with the axis passing through the center of gravity of vane 14 so that the vane will always be in sensitive equilibrium. The diverting vane 14 may be formed entirely of magnetic material, or at least the part 14a thereof extending about bearing 42, and the control chamber 13 may be formed entirely of non-magnetic material, or at least the wall 13b thereof. This enables the sensitive diverting vane 14 to be tilted selectively from its vertical position within the sealed control chamber 13 by means of the magnetic action exerted through wall 13b by an external permanent magnet 44 which may be mounted on the pivot shaft 45 coaxially with vane 14 so as to be operated by a sensitive helical bimetallic temperature responsive element 46. As shown, one end of the thermostatic element 46 is secured to the magnet 44 while the other end is secured to an adjusting member 47 which engages with a friction member 47a. Thus the adjusting member 47 may be operated manually or otherwise to position the thermostatic element 46 so as to hold magnet 44, and consequently vane 14, in different predetermined angular positions at different predetermined temperatures of element 46. Suitable stops

48 may be provided for limiting the maximum angular displacement of the magnet 44 and thus of the diverting vane 14.

Operation

Only with the vaporizer heat supply pipe 17 continuously supplied with steam or other heating medium, any condensate in the vaporizing chamber 10 will continuously receive heat from the portion of the pipe 17 enclosed within this chamber until vaporized. Consequently, as the vaporizing chamber 10 is supplied with more condensate, more vapor will be continuously supplied through conduit 20 to the condenser 11. Thus the rate of heat transfer between the vaporizer 10 and the condenser 11 will depend upon the amount of condensate that is supplied to the vaporizer 10. As previously pointed out, the part of the condensate drained from the condenser 11 through conduit 21 is always returned directly to the vaporizer 10 to be recirculated to the condenser 11.

As long as the control vane 14 remains positioned vertically as shown in Fig. 1, the part of the condensate drained from condenser 11 through conduit 22 will be returned to the vaporizing chamber 10 through the conduit 24 and the conduit 23. Likewise with the diverting vane 14 vertical, the stream of condensate continuously circulated from the accumulating chamber 12 through the thermosiphon loop 30 to the control chamber 13 will be returned into the accumulating chamber 12 through the passage 26. Thus, as long as the rate of heat release obtained from the condenser 11 is sufficient to maintain the temperature to which the thermostatic element 46 is responsive at the desired equilibrium value, the diverting vane 14 will be maintained vertical. Under such equilibrium conditions, the interconnected multiple condensate circulations involved in the improved system are maintained constant.

However, when the temperature to which thermostatic element 46 is responsive decreases from the desired equilibrium value due to an increase in the heating load, then the thermostatic element will rotate the magnet 44 so as to tilt the diverting vane 14 in a counterclockwise direction from its vertical position, as shown in Fig. 1. As a result the condensate flow directing vane 14 will intercept a progressively increasing portion of the condensate circulated to the control chamber 13 through the conduit 30 by the continuously acting thermosiphon pump, and direct this condensate from the accumulating chamber 12 into the vaporizer 10 through conduits 24 and 23. The resulting progressive increase in the amount of condensate in the vaporizer 10 will produce a correspondingly increased rate of heat transfer between the vaporizer 10 and the condenser 11 so as to progressively increase the rate of heat dissipation from the condenser and thereby gradually raise the temperature to which thermostatic element 46 is responsive. As the temperature returns to the desired equilibrium value, the thermostatic element 46 will move the deflecting vane 14 toward the vertical position so that the increased rate of heat transfer will balance the increased heating load. In this way, the improved control system provides a substantially flat temperature regulation since equilibrium of the condensate flow is attained only at the desired equilibrium temperature value.

When the temperature to which the thermostatic element 46 is responsive increases due to a decrease in the heating load, then the magnet 44 will be rotated by thermostatic element 46 to tilt the control vane 14 in a clockwise direction

from the vertical position in which it is shown in Fig. 1. In this case, the condensate received from condenser 11 into the control chamber 13 through the conduit 22 will be intercepted and directed by vane 14 through the passage 26 into the condensate accumulating chamber 12 in an amount dependent upon the increase in temperature to which element 46 is responsive. As a result, the amount of condensate returned to the vaporizing chamber 10 is decreased to produce a corresponding decrease in the rate of heat transfer to the condenser 11 so as to rebalance the heat dissipation thereof with the decreased heating load when the desired equilibrium temperature is attained.

Thus the improvements of the present invention enable the relatively feeble operating force exerted by the sensitive thermostat 46 upon very slight deviations of the desired equilibrium temperature to vary the rate of heat transfer between the vaporizer 10 and the condenser 11 over a relatively wide range due to the cumulative self-amplification of the thermostatic control power provided by the improved selective condensate flow control system. Moreover, the improved variable heat transfer rate control system is a self-contained unitary part of the vapor heat transfer system and operates entirely mechanically, and hence needs no connection to any outside source of power other than the heat supply source of the vaporizer, all of which is of material advantage in adapting the improved heat transfer system to a wide field of temperature regulating service. For room temperature control service the condenser 11 may dissipate heat directly to the room and the thermostat 46 may operate the control vane so as to vary the heat output of the condenser to the room directly in response to room temperature variations. In the case of water heaters, a water temperature responsive thermostat may readily be arranged to vary the transfer of heat from the condenser 11 to the water. No technical obstacles are encountered in applying the improved heat transfer control system to other automatic temperature regulating service.

What I claim as new and desire to secure by Letters Patent of the United States is:

1. A circulating fluid vaporizing and condensing heat transfer system including a vaporizer, a condenser, a condensate accumulating reservoir, a condensate flow control chamber having separate drain connections with said reservoir and said vaporizer to supply condensate thereto and connected with said condenser to receive condensate therefrom, and means including a tilting flow directing vane pivotally mounted in said control chamber for directing the condensate received therein selectively to said vaporizer drain connection and to said accumulating reservoir drain connection.

2. An automatic variable rate circulating fluid vaporizing and condensing heat transfer system including a vaporizer, a condenser, a condensate accumulating chamber, a condensate flow control chamber connected with said condenser to drain condensate therefrom and having a drain connection for supplying condensate to said vaporizer and a separate drain connection for supplying condensate to said accumulating chamber, condition responsive means having a pivoted flow directing vane in said control chamber rotatable oppositely from a predetermined position for selectively directing condensate respectively to said vaporizer drain connection and to said

5 accumulating chamber drain connection, and means dependent upon the supply of heat to said vaporizer for returning condensate from said accumulating chamber to said control chamber to be selectively directed by said vane.

3. An automatic variable rate circulating fluid vaporizing and condensing heat transfer system including a vaporizer, a condenser, a condensate accumulating reservoir, a dual condensate flow control chamber having communication with said condenser to drain a stream of condensate therefrom and with said vaporizer to supply said stream of condensate thereto and having separate communication with said accumulating reservoir to receive a separate stream of condensate therefrom and to return said condensate thereto, means for pumping said separate stream of condensate, and condition responsive means having a pivoted vane in said chamber rotatable oppositely from a predetermined position for selectively directing said streams of condensate respectively to said vaporizer and to said accumulating chamber.

4. A circulating fluid vaporizing and condensing heat transfer system including a vaporizer, a condenser, a condensate accumulating reservoir, a dual condensate flow control chamber connected between said vaporizer and said condenser to circulate condensate therebetween, said control chamber having separate condensate circulating connections with said accumulating reservoir including a pumping means for circulating condensate therebetween, and means including a vane in said control chamber movable oppositely from a predetermined neutral position to direct the condensate received therein from said condenser to said accumulating reservoir and to direct the condensate received therein from said accumulating chamber to said vaporizer.

5. A sealed circulating fluid vaporizing and condensing heat transfer system including a vaporizer, a condenser, a condensate accumulating reservoir, a dual condensate flow control chamber having a non-magnetic wall and a condensate

45 drain connection to said vaporizer in substantial vertical alignment with a condensate drain connection from said condenser to circulate condensate therebetween and having a condensate drain connection to said accumulating chamber in substantial vertical alignment with a condensate supply connection therefrom, continuously operable means for pumping condensate through said supply connection, a movable condensate diverting element mounted in said control chamber for selectively diverting the condensate received therein from said condenser drain connection to said accumulating chamber drain connection and the condensate received therein from said supply connection from said accumulating chamber to said drain connection to said vaporizer, and means including a magnet operable adjacent said wall for moving said diverting element.

6. A circulating fluid vaporizing and condensing heat transfer system including a vaporizer, a condenser having a pair of condensate drain connections therefrom, one communicating directly with said vaporizer, a condensate accumulating reservoir, a dual condensate flow control chamber having communication with said vaporizer to drain condensate thereto and with the other of said drain connections from said condenser to receive condensate drained therefrom and with said accumulating chamber to drain condensate thereto, means for pumping condensate from said

accumulating chamber to said control chamber, and means including a tilting diverting element pivotally mounted in said chamber for diverting the condensate received therein selectively to said vaporizer or to said accumulating chamber.

7. A circulating fluid vaporizing and condensing heat transfer system including a vaporizer, a dual drain condenser having one drain thereof connected in direct condensate return relation with said vaporizer, a condensate accumulating reservoir, a dual condensate flow control chamber interconnected between the other drain of said condenser and said vaporizer to control the return of condensate therebetween and having separate condensate drain connections with said accumulating reservoir, and means including a tilting flow diverting element in said chamber for diverting the condensate received therein selectively to said vaporizer and to said accumulating chamber.

8. A circulating fluid vaporizing and condensing heat transfer system including a vaporizer, a condenser, a condensate accumulating chamber, a dual condensate flow control chamber having communication with said vaporizer to supply condensate thereto and with said condenser to receive condensate therefrom and with said accumulating chamber to supply condensate thereto and to receive condensate therefrom, means including a vane movable in said chamber for diverting the condensate received therein selectively to said vaporizer or to said accumulating chamber, means including a magnet for moving said vane, and continuously operating pumping means for supplying condensate from said accumulating chamber to said control chamber.

9. A circulating fluid vaporizing and condensing heat transfer system including a vaporizer having a continuous heat supply means, a condenser, a condensate accumulating chamber, a condensate flow control chamber communicating with said vaporizer to supply condensate thereto and with said condenser to receive condensate

therefrom and with said accumulating chamber to supply condensate thereto and to receive condensate therefrom, means including a movable element in said chamber for diverting the condensate received therein selectively to said vaporizer or to said accumulating chamber.

5 10. A circulating fluid vaporizing and condensing heat transfer system including a vaporizer or to said accumulating chamber, means including a magnet for positioning said diverting element, and thermosiphon pumping means in heat transfer relation with said continuous heat supply means for continuously pumping condensate from said accumulating chamber to said control chamber.

15 10. A circulating fluid vaporizing and condensing heat transfer system including a vaporizing element, a condensing element, a condensate accumulating element, condensate flow control means communicating with each of said elements and including a movable member for directing condensate from said condensing element selectively to said vaporizer and to said accumulating element, and pumping means for supplying condensate from said condensate accumulating element to said movable member to be directed under the selective control thereof to said vaporizing element and to said accumulating element.

20 11. A circulating fluid vaporizing and condensing heat transfer system including a vaporizing element, a condensing element, a condensate accumulating element, a pumping element for pumping condensate from said accumulating element, and condensate flow control means having separate communication with each of said elements and including a three-position movable control member having one position for directing the flow of condensate from said condensing element and from said pumping element respectively to said vaporizing element and to said accumulating element and two other positions, one for directing all said condensate to said vaporizing element and the other for directing all said condensate to said accumulating element.

MARCUS E. FIENE.
